Primary Examiner — Mark Goodwin

(57) **CLAIM**

The ornamental design for an operator station floor mat, as shown and described.

DESCRIPTION

FIG. 1 is a perspective view of an operator station floor mat showing our new design.

FIG. 2 is a left side view thereof.

FIG. 3 is a right side view thereof.

FIG. 4 is a front view thereof.

FIG. 5 is a rear view thereof.

FIG. 6 is a top view thereof; and,

FIG. 7 is a bottom view thereof.

The broken line representations of environmental structure in FIGS. 1-7 is for illustrative purposes only and forms no part of the claimed design.

1 Claim, 7 Drawing Sheets
